US00D815073S

(12) **United States Design Patent** (10) **Patent No.:** **US D815,073 S**
(45) **Date of Patent:** **** Apr. 10, 2018**

(54) **ANTENNA**

(71) Applicant: **Antennas Direct, Inc.**, Ellisville, MO (US)

(72) Inventors: **Corey Feit**, St. Louis, MO (US); **John Edwin Ross, III**, Moab, UT (US); **Richard E. Schneider**, Wildwood, MO (US)

(**) Term: **15 Years**

(21) Appl. No.: **29/580,046**

(22) Filed: **Oct. 5, 2016**

Related U.S. Application Data

(63) Continuation-in-part of application No. 14/308,422, filed on Jun. 18, 2014, now abandoned, and a continuation-in-part of application No. 29/430,632, filed on Aug. 28, 2012, now abandoned, which is a continuation-in-part of application No. 29/376,791, filed on Oct. 12, 2010, now Pat. No. Des. 666,178, said application No. 14/308,422 is a continuation-in-part of application No. 13/759,750, filed on Feb. 5, 2013, now Pat. No. 8,994,600, which is a continuation-in-part of application No. 12/606,636, filed on Oct. 27, 2009, now Pat. No. 8,368,607, which is a continuation-in-part of application No. 12/050,133, filed on Mar. 17, 2008, now Pat. No. 7,609,222, which is a continuation-in-part of application No. 29/304,423, filed on Feb. 29, 2008, now Pat. No. Des. 598,433, said application No. 12/606,636 is a continuation-in-part of application No. 12/040,464, filed on Feb. 29, 2008, now Pat. No. 7,839,347, said application No. 12/606,636 is a continuation-in-part of application No. 29/305,294, filed on Mar. 17, 2008, now Pat. No. Des. 604,276, which is a (Continued)

OTHER PUBLICATIONS

Notice of Allowance for U.S. Appl. No. 29/587,280, filed Dec. 12, 2016 which claims priority to the same parent application as the instant application, dated Oct. 27, 2017, 10 pages.

Primary Examiner — John Windmuller

Assistant Examiner — Benjamin Weeks

(74) *Attorney, Agent, or Firm* — Harness, Dickey & Pierce, P.L.C.

(57) **CLAIM**

The ornamental design for an antenna, as shown and described.

DESCRIPTION

FIG. 1 is a perspective view of an antenna, showing our new design;

FIG. 2 is a back perspective view of the antenna shown in FIG. 1;

FIG. 3 is a front view of the antenna shown in FIG. 1;

FIG. 4 is a back view of the antenna shown in FIG. 1;

FIG. 5 is a right side view of the antenna shown in FIG. 1;

FIG. 6 is a left side view of the antenna shown in FIG. 1;

FIG. 7 is a top view of the antenna shown in FIG. 1; and,

FIG. 8 is a bottom view of the antenna shown in FIG. 1.

1 Claim, 6 Drawing Sheets

Related U.S. Application Data

continuation-in-part of application No. 12/040,464, filed on Feb. 29, 2008, now Pat. No. 7,839,347, and a continuation-in-part of application No. 12/050,133, filed on Mar. 17, 2008, now Pat. No. 7,609,222, said application No. 12/606,636 is a continuation-in-part of application No. PCT/US2008/061908, filed on Apr. 29, 2008, and a continuation of application No. 12/040,464, filed on Feb. 29, 2008, now Pat. No. 7,839,347, and a continuation of application No. 12/050,133, filed on Mar. 17, 2008, now Pat. No. 7,609,222.
